FOUNTAIN PEN

Simon L. Ruskin, New York, N. Y.

Application September 7, 1939, Serial No. 293,816

6 Claims. (CL 120—47)

This invention relates to fountain pens.

A basic object of this invention is to provide a pen of simple and inexpensive construction and having optimum ink capacity.

5 Another object of this invention is to provide a pen barrel so constructed that when mechanism of the self-filler type is embodied therein no packing is required to prevent leakage of ink from the barrel head.

10 More specifically, this invention has for an object the provision of a fountain pen barrel made initially with both ends open, in one end of which is seated the usual pen-point and feeder assembly, while the other end is closed by an elastic, impermeable member, capable of and adapted to be pierced by a sharp-pointed instrument without resulting possibility of leakage at the site of piercing, whether said instrument be retained by the member or removed therefrom. The preferable material for this closure member is gum rubber, which is impermeable to ink and when pierced by a sharp instrument has the characteristic, when the instrument is removed, of itself closing the hole produced by said instrument; or, when the instrument is permitted to be retained by the member, tightly grips the said instrument to make a water-tight and practically air-tight seal between the two.

15 One phase of my invention involves the provision of a fountain pen unit consisting merely of a barrel having at one end the pen-point and feeder assembly and at the other end the closure member of the characteristics enumerated above.

20 With such a unit the pen may be filled with ink by piercing the said member with a hollow needle attached to a bulb or other type of syringe filled with ink and injecting the ink into the barrel. In this instance, when the barrel is filled, the needle is withdrawn and the hole at the point of piercing automatically closes up so that 25 no ink leakage occurs therethrough.

Another phase of this invention involves the incorporation of self-filler means into the pen. 30 A simple and satisfactory device for this purpose comprises a stem passing through the said closure member and extending into the barrel, at the inner end of which stem is affixed a disc or washer type piston element, while the outer end of the stem is adapted for manual operation in the usual manner. Since the closure member has a water-tight grip about the stem, no ink leakage occurs from the barrel at that end and consequently the necessity for any packing is eliminated. Since ordinarily this packing occupies a

considerable part of the barrel, its elimination increases the available ink capacity of the barrel considerably.

In practice, it has been found most satisfactory to make the elastic closure member cup-shaped and cementing the skirt thereof to the barrel. The thickness of the portion across the open top of the barrel should not be so thin as to tear readily and not so thick as to unduly resist penetration by the needle or the stem, as the case may be; nor unduly resist reciprocation of the stem. Nor should the closure cap be so elastic as to be unduly distended by the reciprocal movement of the stem, since the closure member is not relied on as a means in expelling air from the barrel.

When the self-filler mechanism is employed, the diaphragm part of the closure member is made thick enough to support the stem in an upright position and to reasonably resist any side play thereof. The stem should be made as thin as practicable consistent with the required amount of rigidity to permit the stem to be reciprocated without requiring undue force. A suggested substitute for gum rubber out of which to form the closure cap is the rubber-like polymethylacrylate derived casein; other equivalent substances may be used.

Other features and objects of this invention appear in the ensuing description and drawing, wherein

Fig. 1 is a sectional view through the basic fountain pen unit;

Fig. 2 shows one means and mode of filling the same;

Fig. 3 shows a modification of Fig. 1;

Fig. 4 shows another modification; and

Fig. 5 is a sectional view of my basic unit with which is incorporated a suggested and practical form of self-filler mechanism.

Referring to the several figures, my fountain pen comprises a barrel 1 made with both ends open, in one end of which is placed the pen-point 2 and feeder 3 assembly, while the other end is capped with a cup-shaped closure member 4 made of gum rubber or equivalent material, providing a penetrable diaphragm portion 5 across the open end of the barrel. The skirt 6 of the member 4 is preferably cemented, as indicated at 7, to the barrel, and the rim of the member 4 is provided, for preference, with a bead 8. In this form, the pen may be filled by piercing the diaphragm portion 5 through with a hollow needle 9 attached to the bulb 10 of a syringe 11 (Fig. 2). When the needle is removed, the hole produced by the pier-

ing act immediately closes up by itself so that no ink-leakage occurs therethrough.

In Fig. 3, the top of the barrel has a set-back extension $1a$ for receiving the member 4 , while in Fig. 4, the barrel is formed with a bead 12 , while the rim of the member $4a$ is formed without a bead.

In Fig. 5 there is disclosed a self-filling mechanism associated with the basic unit shown in Fig. 1. This mechanism comprises a plunger or piston 13 consisting of a stem 14 at the inner end of which is mounted a piston head 15 consisting of a disc or washer 16 , of rubber or other suitable material, positioned between the flanged end 17 of the stem and a nut 18 , preferably of the self-locking type, threaded on the portion $18'$ of said stem. The nut 18 is threaded down tightly so as to clamp the washer 16 securely in place, and the nut 18 and flange 17 are of extensive width to hold the washer 16 rigid against deformation. The upper end of the stem is pointed, as shown at 19 and screw-threaded as shown at 20 , below the pointed end for a predetermined distance. In placing the plunger into the barrel for operative use, the said plunger is pushed, piston head first, into the barrel before the cap 4 is attached. The said cap is then centrally positioned over the pointed end of the stem and the cap forced down, causing the point of the stem to penetrate through the said cap. The cap is then cemented, or otherwise attached, to the barrel, as shown in Fig. 1, 2 or 3. A nut or internally threaded washer 21 is then spun down the threaded portion 20 of the stem. A reciprocable tubular member or headed sleeve 22 is then slid over the barrel 1 , the head 23 of which member 22 is provided with a central bore 24 communicating with an enlarged counterbore 25 . When the said sleeve is in telescoped position over the barrel the upper end of the stem projects through the bore 24 and into the counterbore 25 . The shoulder 26 cooperates with the washer 21 to limit the downward movement of the sleeve, while the said shoulder acts as a stop for an internally-threaded cap 27 which threads onto the portion 20 and has a slotted head for the accommodation of a screw-driver. The head of the cap 27 can be made polygonal in shape so as to permit it to be manipulated by the fingers. With said cap 27 tightly screwed down the stem is held firmly attached to the headed sleeve.

Preferably the internal diameter of the sleeve 22 is such that it is somewhat less than the external diameter of the beaded portion of the rubber cap 4 , so that there will be a snug fit between the two. This fit should, by preference, be tight enough to prevent undesired or accidental movement of the sleeve along the barrel. The diaphragm portion 5 of the cap 4 should be of sufficient thickness to resist tearing when pierced by the needle or stem aforesaid, though not so thick as to require undue force to secure reciprocation of the plunger.

Should it be necessary to replace the rubber cap or parts of the plunger, access thereto for this purpose is readily achieved by removing the cap 27 . This permits the sleeve 22 to be removed, exposing the rubber cap, and enabling both the

latter and the plunger to be removed for repair or replacement needs.

The lower end of the sleeve 22 is tapered somewhat so that when the sleeve is retracted to the full intake position (shown in dotted lines in Fig. 5 in part full position), the said tapered end will come in contact with the head 8 of the cap 4 , the limit of retraction being indicated by the resistance offered by the bead against further withdrawal, though the sleeve can be removed by forcing retraction.

The bead 8 has another function: that of acting as a shock absorber should the pen be dropped, thus assuring against possible bending or breaking of the stem.

Positive provision against involuntary movement of the sleeve and plunger is made by providing the upper portion of the barrel with a screw-threaded section $1b$ and the lower end of the sleeve 22 with screw-thread $22a$ and screwing the said sleeve-end onto the section $1b$ of the barrel.

Having described my invention, what I claim is:

1. A fountain pen comprising a barrel, a pen-point and feeder assembly mounted in one end thereof, a cup-shaped gum rubber closure member over the other end thereof, said member having an external annular bead around the skirt thereof, suction-creating mechanism mounted in said barrel and having a stem projecting through said member, and a reciprocable tubular cap having a restricted mouth connected to said stem and extending down the barrel in telescopic relation therewith beyond the said bead, said bead being in frictional engagement with the inside of said reciprocable member and acting as a stop for said cap.

2. A fountain pen comprising a rigid tubular barrel having a pen point and feeder assembly mounted in one end thereof and a self-closing and impermeable cap positioned over and closing the opposite end of said barrel.

3. A fountain pen comprising a rigid tubular barrel having a pen point and feeder assembly mounted in one end thereof and a gum rubber cap closing the opposite end of said barrel.

4. A fountain pen comprising a rigid barrel having a pen point and feeder assembly mounted in one end thereof, a self-closing and impermeable closure mounted upon the other end of said barrel and suction-creating mechanism detachably carried by and extending through said closure and being operated exteriorly of the closure.

5. A fountain pen comprising a rigid barrel having a pen point and feeder assembly mounted in one end thereof, a self-closing and impermeable cap closing the opposite end of said barrel, a relatively thin tube detachably positioned through said cap and a compressible bulb connected to the end of said tube exteriorly of the barrel bore.

6. A fountain pen comprising a rigid tubular barrel having a pen point and feeder assembly mounted in one end thereof and a member formed from a self-closing and impermeable material stretched across and closing the opposite end of said barrel.
